INVENTOR
Donald P. Stevens
BY HIS ATTORNEY:

A. M. Carlsen.

UNITED STATES PATENT OFFICE.

DONALD P. STEVENS, OF ST. PAUL, MINNESOTA.

SMOKING PIPE.

Application filed November 11, 1920. Serial No. 423,239.

To all whom it may concern:

Be it known that I, DONALD P. STEVENS, a citizen of the United States, residing at St. Paul, in the county of Ramsey and State 5 of Minnesota, have invented a new and useful Smoking Pipe, of which the following is a specification.

My invention relates to smoking-pipes, and the object is to provide tobacco smokers 10 with a pipe that will not easily clog and from which the creosote of the nicotine may readily be removed and needs only be removed at long intervals since an extra large surface is provided for holding it.

15 The accompanying drawing is a longitudinal vertical section of a smoking-pipe embodying my improvements.

In said drawing 1 designates the bowl of the pipe and may be made of briar or any 20 other suitable material, its tobacco space or bore 2 is preferably hemispheric in the bottom and is provided in its rear side with an aperture 3, which is closed by the front side of a metallic thimble 4 having a small aperture 25 for the smoke to pass through from the tobacco, as indicated by the arrow 6. Said thimble is forced into the bore 7 of the bowl where it may be held by friction or other suitable means. The thimble is of so 30 thin sheet metal that the aperture 5 does not form a duct of sufficient length for nicotine or its products to lodge therein.

Inserted and suitably held in the rear part, 1^a, of the bowl is the tubular stem 8 of 35 the pipe, and in said stem is removably held the mouthpiece 9 having the smoke duct 10.

Detachably secured in the lower end of the mouthpiece is a tube 11 having its lower end 12 flared or funnel shaped. And spaced 40 about said tube is a larger tube 13 which is also detachably secured to the mouthpiece but has its bottom end 14 closed and preferably bowl shaped and spaced some distance below the funnel 12. The upper end 45 of the forward side of the tube 13 is provided with a smoke inlet aperture 15.

In the use of the pipe the smoke is caused

to pass as indicated by the arrows 6, 6^a, 6^b to the mouth piece and while the smoke is thus moving along, its nicotine is deposited 50 upon the surfaces 16, 17, 18, 19 of the tubular parts of the pipe, but no nicotine can be drawn into the tube 11, because if any nicotine should form liquid enough upon said tube to flow down along its outer side, the 55 funnel 12 will prevent its entering into the tube and will cause it to drip down and accumulate as at 20 in the bowl 14. Likewise if any nicotine forms a flowing liquid on the surfaces 16, 17, and in the bore 7 it will 60 gather as 21 in the thimble 4.

If the nicotine 20 threatens to cover the inner opening of the funnel 12 the pipe will make a bubbling sound and thereby inform the user, who will then take the pipe apart 65 and clean out all the liquid nicotine and also wipe clean all the surfaces of the parts and assemble them again.

What I claim is:

In a smoking pipe the combination of a 70 bowl having a vertical bore for tobacco, a rearward bore for receiving a stem, a stem therein, a mouth piece detachably secured to the stem, and detachably secured to the lower end of the mouthpiece and spaced 75 within the stem a tube having its lower end closed and the upper end of its front side provided with a smoke aperture, a smaller tube spaced within the said closed tube and having its upper end held in the mouth- 80 piece and its lower end open and spaced from the bottom of the closed tube, a re-duced bore within the bowl and opening into said rearward bore, the forward end of said reduced bore being semi-spherical and 85 opening into the vertical bore of the bowl, and a thin metallic thimble fitted into the semi-spherical end of the reduced bore and closing the opening into the vertical bore of the bowl, and having an aperture in its 90 upper side opening into the vertical bore of the bowl.

In testimony whereof I affix my signature.

DONALD P. STEVENS.
